UNITED STATES PATENT OFFICE.

ALFRED I. CROOK, OF PHILADELPHIA, PENNSYLVANIA, ASSIGNOR TO PHILADELPHIA ROLL AND MACHINE COMPANY, OF PHILADELPHIA, PENNSYLVANIA, A CORPORATION OF PENNSYLVANIA.

ROLLING-MILL.

1,370,291.

Specification of Letters Patent.

Patented Mar. 1, 1921.

Application filed May 10, 1916. Serial No. 96,597.

To all whom it may concern:

Be it known that I, ALFRED I. CROOK, a citizen of the United States, residing in Philadelphia, Pennsylvania, have invented 5
5 Rolling-Mills, of which the following is a specification.

My invention relates to 3-high rolling mills of the type having a fixed center line or middle roll, and has for one of its objects the provision of novel means for carrying or supporting the top roll of such a mill.

It is further desired to provide a novel system of counter weights with the necessary 15 connecting members, for supporting the top roll of a 3-high mill of the type noted;—the arrangement being such that the struts employed are guided or movable within, the body of the housing of the mill, while the 20 bearings supported by said struts include projections extending into vertical recesses in said housing whereby they are retained in place and vertically guided.

The invention also contemplates the provision of a novel arrangement of wedges for 25 adjusting and locking in place the bearing structures for the middle roll of the mill, and contemplates such an arrangement of parts and disposition of material as will 30 make the mill substantial as to structure and satisfactory as to operation.

These objects and other advantageous ends I secure as hereinafter set forth, reference being had to the accompanying drawings, in which,

Figure 1 is an end elevation, partly in section, of a 3-high rolling mill constructed according to my invention;

Fig. 2 is a side elevation, partly in vertical section, further illustrating the mill shown in Fig. 1;

Fig. 3 is a plan of the counter-weights and their associated levers;

Fig. 4 is a fragmentary vertical section on 45 a larger scale taken in the plane of one pair of bearing-supporting struts;

Fig. 5 is a horizontal section on the line 5—5, Fig. 4; and

Fig. 6 is a perspective view of one of the 50 wedges employed between the pillow blocks associated with the middle roll.

In the above drawings 1 represents a pair of substantially parallel tracks or guides

upon which are mounted the two housings 2 of the mill, and each of these is provided 55 with the customary retaining cap 3 held in position by bolts 4. In the bottom of the vertically extending guideway of each housing is mounted a pillow block 5 supported upon a threaded shaft 6 which passes 60 through a nut 7 carried in a suitable recess in the central lower part of the housing structure. The lower end of each of the shafts 6 has fixed to it a gear 8 engaging a long faced pinion 9 supported upon a shaft 65 10 carried in a vertical bearing 11 fixed to the outer face of the housing structure to which it is attached. Any suitable means, such as a handle 12, may be employed for turning said shaft 10 at will in order to 70 actuate the corresponding shafts 6 and raise or lower the pillow block 5.

Each of the pillow blocks 5 carries a bearing 13 in which rests one end of the lower roll 14. Above said pillow blocks the vertical guideway of each of the housings is laterally extended for the reception of a pair of pillow blocks 15 and 16, of which the lower is solidly supported upon projecting ledges of said housings and carries a bearing 17 which serves to support the middle roll 19 so that its axis is at all times fixed relatively to the remainder of the frame.

For the purpose of adjusting the distance between each pair of the pillow blocks 15 85 and 16, I insert a pair of wedges 20 between them on either side of the neck of the roll and form each of the wedges with an overhung head through which passes a threaded stud 21. Each of these studs has a nut 90 whereby its wedge may be forced inwardly between the pillow blocks 15 and 16 so as to move them to and fro and retain them at any given distance apart.

The upper pillow block 16 with its bearing 95 18 is adjustably forced toward the pillow block 15 and held in any given position, by means of a second pair of wedges 22 inserted between it and a suitable overhung part of the housing structure. These wedges like 100 the others, have turned over ends engaging studs 23 provided with nuts, whereby said wedges may be forced inwardly when desired. The pillow block 15 is held in the housing by a pair of plates 24 held to the 105 outer face of said pillow block by nuts 25.

Similarly each of the upper pillow blocks is held in place by plates 26 engaging its outer face and held in position by nuts on bolts 27.

The housings above the fixed-center mid-
dle roll have their adjacent faces verti-
cally slotted for the reception of the pro-
jecting ends 28 of a lower bearing 29 car-
rying the top roll 30. Each of said bear-
ings is carried upon a pair of rods 31 con-
stituting struts which extend through elon-
gated guideways or channels in each of the
housings and at their lower ends respec-
tively engage the short arms 32 of levers
fulcrumed to links 33 hung to the lower
part of the housing structure. The long
arms 34 of said levers extend toward and
past each other as shown in Fig. 3, and have
attached to their extremities counter weights
35 which are suspended approximately mid-
way between the two housings 2.

The upper roll 30 is also engaged by up-
per bearings 36 held in place by pillow blocks
37 guided in the respective housings and car-
rying blocks 38 engaged by the lower ends of
screws 39 threaded through suitable nuts
40 in the caps 3. These bolts have hexago-
nal heads whereby they may be screwed up
or down at will or they may be provided
with any other desired means to facilitate
their adjustment.

It is particularly to be noted that with
the above described arrangement of parts,
the position of the upper roll may be accu-
rately adjusted to give a definite, constant
thrust against the upper bearings since it is
yieldingly forced against them by the coun-
ter weights, whose mass is such as to over-
balance said roll and the structures which
it carries. In other words, the weight of
this roll is carried solely by the struts 31
and it is at all times pressed up toward the
bearings 36 by a constant force.

Moreover by the arrangement of parts

shown there is no material interference with
the structural strength of the housings, and 45
the struts are effectually inclosed and pro-
tected within the latter.

By the arrangement of wedges shown the
position of the center roll may be exactly
adjusted and said roll may thereafter be 50
rigidly maintained in its given position
without excessive neck friction.

I claim:—

1. The combination in a 3-high rolling
mill, of housings, two sets of pillow blocks 55
mounted therein, a wedge system for each
set, bearings in the pillow blocks, a nor-
mally fixed-center-line middle roll mounted
in said bearings, top and bottom rolls and
their bearings, means for adjusting the bot-
tom roll, and an equalizing compression
system for the top roll and its bearings
whereby they may be adjusted bodily with-
out disturbing their relation.

2. The combination in a 3-high rolling 65
mill of housings; two sets of pillow blocks
mounted in said housings; wedges operative
between said pillow blocks of each set; bear-
ings in the pillow blocks; a normally fixed-
center-line middle roll mounted in said bear-
ings; a top roll; a bottom roll; and means
for maintaining said latter rolls in opera-
tive relation to the middle roll.

3. The combination in a 3-high rolling
mill of housings; two sets of pillow blocks 75
mounted in said housings; wedges operative
between said pillow blocks of each set;
bearings in the pillow blocks; a normally fixed-
center-line middle roll mounted in
said bearings; a top roll; a bottom roll; 80
means for maintaining said latter rolls in
operative relation to the middle roll; with
wedges operative on the upper pillow block
to retain it in any position to which it has
been adjusted by said first wedges.

ALFRED I. CROOK.
